PACKAGING DISPLAY TRAY

Richard F. Reifers, New Canaan, Conn., assignor to
Diamond International Corporation, New York, N.Y.

Original design application Dec. 17, 1970, Ser. No.
26,551, now Patent No. 224,735, dated Sept. 12,
1972. Divided and this application Aug. 30, 1971,
Ser. No. 176,423

Term of patent 14 years

Int. Cl. D9—03

U.S. Cl. D9—243

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 1 is a perspective top view of a packaging display tray showing my new design;

FIG. 2 is a plan view of the tray shown in FIG. 1;

FIG. 3 is a side elevation view of the tray shown in FIG. 1;

FIG. 4 is a sectional view taken along line 4—4 of the tray shown in FIG. 3;

FIG. 5 is a bottom view of the tray shown in FIG. 1;

FIG. 6 is an end elevation of the tray shown in FIG. 1;

FIG. 7 is a top perspective view of a modified form of the design of FIG. 1 wherein the end walls have corner projections thereon;

FIG. 8 is a plan view of the tray shown in FIG. 7;

FIG. 9 is a side elevation view of the tray shown in FIG. 7;

FIG. 10 is a sectional view taken along line 10—10 of the tray shown in FIG. 9;

FIG. 11 is a bottom view of the tray shown in FIG. 7; and

FIG. 12 is an end elevation of the tray shown in FIG. 7. This application is a division of application Ser. No. D. 26,551, filed Dec. 17, 1970, now Pat. No. D. 224,735, patented Sept. 12, 1972.

I claim:

The ornamental design for a packaging display tray, as shown and described.
